WINDING MACHINE

Robert Pash, Roselle, N. J., assignor to Western Electric Company, Incorporated, New York, N. Y., a corporation of New York

Application March 3, 1939, Serial No. 259,501

6 Claims. (Cl. 242—4)

This invention relates to winding machines, and more particularly to machines for winding an insulated electrical conductor upon a toroidal core.

5 Electrical coils having a doughnut shaped or toroidal core of magnetic material with a winding of insulated electrical conductor strand wound thereon in turns passing through the central aperture of the core have innumerable applications in the electrical arts, especially in 10 the communications arts. Perhaps the most satisfactory and efficient class of machine for winding such coils is that in which a peripherally grooved spool ring, containing in the groove a 15 supply of wire to be wound on a toroidal core, and a closely associated guide ring, having means to take wire from the spool ring and lay it on the core, are both interlinked with the core to be wound. A typical machine of this class is minutely disclosed and described in U. S. Patent 20 1,994,661 issued March 19, 1935, upon an application by the present inventor. In such a machine, the spool ring and guide ring are in a plane perpendicular to the plane of the core and pass 25 through the center of the core. However, since the two rings are ordinarily of considerably greater diameter than the core, the latter does not pass through the two rings at their common center, but at a point between their center and 30 their peripheries. Hence, when the core is being wound, the portion of wire extending from the spool ring over the guide of the guide ring and to the core varies cyclically in length. Therefore there arises a difficult problem in 35 maintaining the constant, though small, linear tension upon the portion of wire being wound which is required in order to lay the wire in substantially even turns and smooth layers on the core without allowing slack to appear, on the one hand, or, on the other, over-stressing the often fine and delicate wire.

An object of the present invention is to provide improved means, in a machine of the general character described, for imposing a satisfactorily constant adjustable tension on the wire being wound on a toroidal core.

With the above and other objects in view, the invention may be embodied in a machine for winding toroidal coils and comprising a spool 50 ring and a guide ring mounted in close juxtaposition to each other and to be rotatable through the aperture of a toroidal core in a plane at right angles to the core, means to drive the guide ring to take strand from the spool ring and wind it 55 on the core while thereby driving the spool ring

in rotation and means to yieldingly resist the rotation of the spool ring and including a brake drum driven by the spool ring, a helical friction member coaxial with and engaging the drum, and adjustable resilient means to control the pressure 5 of the friction member against the drum.

Other objects and features of the invention will appear from the following detailed description of one embodiment thereof taken in connection with the accompanying drawings in which the same reference numerals are applied to identical parts in the several figures and in which—

Fig. 1 is a view in front elevation and partly in vertical section of machine constructed in accordance with the invention;

Fig. 2 is a view thereof in section on the line 2—2 of Fig. 1;

Fig. 3 is a section on the line 3—3 of Fig. 1;

Fig. 4 is a broken detail view on the line 4—4 of Fig. 3;

Fig. 5 is a broken detail view on the line 5—5 of Fig. 3;

Fig. 6 is an enlarged section on the line 6—6 of Fig. 3;

Fig. 7 is an enlarged sectional detail view of 25 the spool ring and guide ring taken on a radius of the spool ring; and

Fig. 8 is a section on the line 8—8 of Fig. 1.

In describing the machine disclosed, only so much of the mechanism will be described in detail as pertains to the present invention, the general organization and operation being described in detail in U. S. Patent 1,994,661, cited above, to which reference may be had for these phases.

A toroidal core to be wound may be held in a 35 horizontal position between the jaws 20 and 21 of a clamping device therefor, generally indicated at 22, and mounted on a vertical shaft 23 in such fashion as to be rotatable horizontally to and fro about the center of the core to distribute the 40 turns of the winding on the core. A spool ring 24 and a guide ring 25 are mounted side by side to be perpendicular to the central plane of a core held in the clamp 22 and to pass through the center of the aperture of the core.

The guide ring 25 is carried on and driven by four pinions 26 which engage an internal gear 27 formed on the ring 25. Each pinion 26 is rigid on one end of a shaft 28 having another pinion 29 secured on the other end, and the four 50 pinions 29 are driven by a common internal gear 30 secured to a disk 31. The disk 31 is driven by two pins 32 mounted therein on which links 33 are pivoted. The other ends of the links 33 are forked, and in each of these forks is rotatably 55

mounted a cam roller 34. The two cam rollers 34 run on an internal cam 35 formed in a stationary member 36. A link 37 is pivoted to each of the links 33 on the pin which is also the axle 5 of the roller 34. The other end of each of the links 37 is pivoted on a pin 38 mounted in a rotatable disk 39 secured to a hollow spring barrel 40. A pair of heavy clock springs 41 is housed in the barrel 40. These springs are secured to their outer ends to the barrel 40 which is rigidly secured to a shaft 42 journaled at 43 in a hollow shaft 44. The inner ends of the springs 41 are secured in a stub shaft 45 integral with or rigidly secured to the disk 31. The springs 41 tend to urge the pins 38 toward the pins 32 and thus keep the rollers 34 at all times in contact with the cam 35.

The disk 39 is driven by one or more pins 46 integral therewith or mounted therein which pass 20 through corresponding bores in a disk 47 parallel and adjacent to the disk 39. The disk 47 also has pins 48 mounted therein, which, in the position of the parts shown, enter corresponding bores 49 in the stationary cam body 36, and thus 25 lock the entire chain of mechanism thus far described against motion. The disk 47, however, is mounted on and slideable with the hollow shaft 44 to release the pins 48 from the member 36 without releasing the pins 46 from the disk 47, 30 the pins 46 being longer than the pins 48. The shaft 44 and disk 47 are yieldingly urged toward the right (Fig. 1) from the position shown by the compression spring 50 which abuts at one end against the closed end of the barrel 40 and at 35 the other end against the journal block 43 secured in the shaft 44. The disk 47 and shaft 44 may be held in the position shown or allowed to be moved to the right by the spring, by a yoked clutch lever 51 secured to a shaft 52 actuatable by a handle not shown. The connecting means between the lever 51 and the shaft 44 are also not shown to avoid further complicating an already complicated showing, but may be of any 40 approved construction for such familiar linkages. 45 The disk 47 is also provided on its right side with one or more pins 53, which, when the disk 47 is moved to right engage a disk 54 integral on a hollow shaft 55 rotatable on the shaft 44 and in bearings 56 supported in the machine frame. The disk 54 is provided in its periphery with a plurality of notches or recesses by which to be engaged by the pin or pins 53. A fly-wheel 57 is keyed on the outer end of the shaft 55 and is driven by a friction wheel 58 mounted on the shaft of a motor 59.

When the parts are in the position shown, used when the spool ring 24 is to be filled as herein-after described, the flywheel 57, shaft 55 and disk 54 run idly so far as the mechanism now under 60 consideration is concerned, while the chain of mechanism from the disk 47 to the guide ring 25 is locked against motion by the pins 48 engaging in the bores 49 of the stationary cam body 36.

When the clutch lever 51 is actuated to shift the shaft 44 and disk 47 to the right (to wind wire from the spool ring by way of the guide ring upon a core in the clamp 22), the disk 54 is engaged by the pins 53 and thus drives the 65 disk 47 at constant rotary speed.

The disk 47 then drives the disk 31 by means of the toggle linkages 33, 37 at a speed of rotation which varies cyclically as the toggles open and close under the effect of the cam 35. This 70 cyclically varying rotation of the disk 31 is then

transmitted through the gear 30 and the pinions 29, shafts 28, pinions 26 and gear 27 to the guide ring 25. The character of, effect, and necessity for this cyclically varying speed of the guide ring is fully explained and discussed in 75 U. S. Patent 1,994,661 already cited.

It may be noted here that both the spool ring 24 and the guide ring 25 are incomplete annuli, each having a gap therein for the introduction of an unwound core and the removal of a wound 10 core. The guide ring 25 carries, at one side of its gap, an overhanging guide lug 60 over which wire being wound passes from the spool ring to a guide sheave 61 mounted on the guide ring, from which the wire passes to the core. 15

The spool ring 24 is supported on a plurality (here three pairs) of grooved rollers 62, each rigid on one end of a shaft 63 having a pinion 64 secured on its other end. All the pinions 64 mesh with a common sun gear 65 formed on the 20 periphery of one end of a hollow outer brake drum 66 rotatably supported in a bearing 67 mounted in the machine frame. Within the drum 66 is an inner brake drum 68 peripherally spaced from the drum 66 and having a helical friction 25 member 69 wound on and secured at one end to the peripheral surface of the inner drum 68, the other end of the friction member 69 being secured to a ring 70 fastened to the back of a dial plate 71. The ring 70 has an integral drum or 30 sleeve 72 coaxially rotatable within the inner drum 68, and twin clock springs 73 housed between the sleeve 72 and the drum 68 are each secured at one end to the drum and at the other end to the sleeve. 35

The dial plate 71 is secured to and carries a gear 74 which is driven by a pinion 76, which in turn is driven by any suitable mechanism (not shown) from the motor 59, but which includes a clutch by which the pinion 76 may be connected to or disconnected from being driven by the 40 motor.

A reserve supply of wire to be wound is coiled on a reel 77 and supported in an angle formed by two flexible belts 78 and 79 driven by the motor 59 through mechanism whose construction and operation form no part of the present invention, except to state that a clutch is included therein to connect the belt driving gearing to or disconnect it from being driven by the motor. 45

Assuming now that the spool ring 24 is empty of wire and that an unwound core has been locked into the clamp 22 to be provided with a winding, wire is drawn manually from the reserve supply reel 77 along the path indicated by the line 80, passed through the center hole in the core and attached to the spool ring 24, as described in the patent cited above. The clutch lever 51 is shifted to the left or left in the leftward position, and thus, as described above, the guide ring 25 and its mechanism are disconnected from the motor and locked against motion. The clutch which controls the pinion 76 is actuated to drive the pinion and the clutch which controls the belts 78 and 79 is also actuated to set these 55 belts in motion. The motor and mechanism are arranged to drive the gear 74 and interlocked dial plate 71 clockwise as seen in Fig. 5, thus driving the ring 70 and its integral barrel 72. The barrel 72 through the spring 73 drives the drum 70 60 on whose outer surface is positioned the helically formed friction member 69. This friction member may preferably be of fabric impregnated and coated with a suitable material such as one of the artificial resins, i. e. the phenolformalde- 75

hyde condensation product known as "Bakelite," or the member 69 may be of any other suitable substance, which will make the member hard, durable and springy.

- 5 The spring 73 is so wound within the drum 68 and the helical member 69 is so coiled on the drum 68 and secured to the ring 70 and the drum 68, that the effort of the spring 73 is to uncoil the member 69, enlarging the diameter 10 of the helix of 69 to press outwardly against the inside of the drum 66. The frictional drag of the helix 69 on the drum 66 will then drive the drum and its integral gear 65, the pinion 64, shafts 63, grooved rolls 62, and the spool ring 24. 15 The spool ring is driven counterclockwise as seen in the direction of Fig. 5, and so takes up wire fed to it along the line 80 from the reserve reel 71.

The drive of the belts 18 and 19 is such that 20 the wire is fed off from the reel 71 a trifle more slowly than the spool ring 24 would take up the wire were there no slip in the mechanism driving the ring 24. Thus the wire being wound up on the spool ring is under a constant tension and is 25 laid on the ring in snug smooth turns since the drum 66 slips on the member 69. The slip of the drum 66 on the helix is such that the drag of the drum on the helix tends to wind the helix itself tighter on the drum 68 and thus to ease the frictional engagement of the member 69 with the drum 66. This effect is resisted by the spring 73.

When the required length of wire from the reel 71 has been wound on the spool ring, which may be indicated by a metering device 81 connected to 30 the mechanism driving the belts 18 and 19, the clutches in the drives of the belts and of the pinion 76 are disconnected. The wire is then cut at the outer end, hooked down out of the way as indicated at 82.

40 The inner end is secured to the core positioned in the clamp 22, and the clutch lever 51 moved to the right, thus connecting the driving mechanism for the guide ring 25. The spool ring clutch is left disconnected. The mechanism is arranged 45 to now drive the guide ring clockwise as seen in Fig. 2 and at the cyclically varying speed of rotation described above. The member 60 and sheave 61 on the guide ring may then take the wire (secured at one end to the core) and lay it around 50 the core in successive turns passing through the central hole of the core. The clamp is turned to and fro to rotate the core back and forth about its center and thus to distribute the turns over a predetermined segment of the core.

55 Wire thus wound on the core is drawn over the member 60 and sheave 61 from the spool ring and the spool ring is thus forced to revolve, in the same direction as the guide ring, at such a rate that its peripheral speed will equal the linear 60 speed of the wire from the spool ring to the core. The cyclic variation of speed of the guide ring is such as to cause the spool ring to be driven at substantially constant rotary speed.

The spool ring, being thus driven, drives the 65 rollers 62, shafts 63, pinions 64, gear 65 and drum 66. The drum 66, by the frictional engagement with the helix 69 tends to drive this last and so the ring 70, dial 71 and gear 74. Some positive stop means could be supplied if necessary to hold 70 the gear 74 and so the helix 69 stationary if necessary. However, it is found in practice that the frictions between the members of the mechanisms behind the gear 74, including the clutch for connecting and disconnecting this gear to and from the motor, are sufficient ordinarily to hold 75

the helix stationary while the drum 66 slides over it. The friction of this drum on the helix then supplies the tension in the strand being wound from the spool ring on the core required to do the winding in smooth, close and even turns. 5

It is to be noted that, both when the spool ring is being driven in one direction to fill it with strand and when it is running in the opposite direction for winding strand on the core, the drum 66 slips on the helix 69 in the same direction relatively to the helix, tending in both instances to coil and narrow the helix on the drum 68, and that this effect is countered by the tension of the spring 73 which tends to uncoil and widen the helix. The tension in the strand 15 whether this is being wound on the spool ring or drawn from it is balanced between the tension of the spring and the frictional drag of the helix on the surrounding drum.

It will be clear that, especially in the case of 20 fine and delicate wire being wound, there must be no shocks originating in and transmitted through the mechanism to the wire. Hence arises the importance of the mechanism particularly disclosed in Fig. 8. It is the interaction between the 25 cam 35 and the cam rollers 34 which governs the alternatingly positive and negative acceleration of the guide ring 25. The interposition in this mechanism of the springs 41 ensures continuous effective contact at all times of the rollers against the cam surface, with consequently enforced smooth variation of the guide ring acceleration and avoidance of any tensional shock to the wire being wound.

The mechanism particularly disclosed in Fig. 6 35 is also important in offsetting the effect of any linear shock to the strand being wound, e. g. such as might well arise from winding the strand on a core having a square, oblong or other radial section, as the strand is laid around one of the 40 corners. The sensitivity of the braking effected by the combination including the springs 73, friction member 69 and drum 66 is such that if the strand be jerked for any reason, the brake releases practically instantaneously and takes 45 hold again at once with gradually increasing effectiveness.

The particular machine herein disclosed as embodying the various features of the invention is illustrative only and may be modified and 50 departed from variously without departing from the spirit and scope of the invention as pointed out in and limited solely by the appended claims.

What is claimed is:

1. A machine for winding toroidal coils, which 55 machine comprises a spool ring to contain a supply of strand to be wound on a toroidal core, a guide ring to withdraw a continuously cyclically varying length of strand from the spool ring and to wind the same on the core, means to drive the 60 guide ring at a cyclically varying rate of rotation to withdraw strand from the spool ring at constant linear speed of the strand and thereby to drive the spool ring at constant speed of rotation, the withdrawal of the strand being the sole 65 means to drive the spool ring, and brake means to resist the rotation of the spool ring and thereby to impose a linear tension upon the strand being wound.

2. A machine for winding toroidal coils, which 70 machine comprises a spool ring to contain a supply of strand to be wound on a toroidal core, a guide ring to withdraw a continuously cyclically varying length of strand from the spool ring and to wind the same on the core, means to drive the 75

- guide ring at a cyclically varying rate of rotation to withdraw strand from the spool ring at constant linear speed of the strand and thereby to drive the spool ring at constant speed of rotation, the withdrawal of the strand being the sole means to drive the spool ring, and adjustable brake means to resist the rotation of the spool ring and thereby to impose a linear tension upon the strand being wound.
10. 3. A machine for winding toroidal coils, which machine comprises a spool ring to contain a supply of strand to be wound on a toroidal core, a guide ring to withdraw a continuously cyclically varying length of strand from the spool ring and to wind the same on the core, means to drive the guide ring at a cyclically varying rate of rotation to withdraw strand from the spool ring at constant linear speed of the strand and thereby to drive the spool ring at constant speed of rotation, the withdrawal of the strand being the sole means to drive the spool ring, and brake means to resist the rotation of the spool ring and thereby to impose a linear tension upon the strand being wound, the said brake means including a rotatable brake member driven by the spool ring, a helical friction member in frictional engagement with the brake member and so formed and wound that the normal drag of the brake member thereon tends to lessen the frictional engagement, and spring means to yieldingly maintain the frictional engagement.
4. A machine for winding toroidal coils, which machine comprises a spool ring to contain a supply of strand to be wound on a toroidal core, a guide ring to withdraw a continuously cyclically varying length of strand from the spool ring and to wind the same on the core, and means to drive the guide ring at a cyclically varying rate of rotation to withdraw strand from the spool ring at constant linear speed of the strand and thereby to drive the spool ring at constant speed of rotation, the withdrawal of the strand being the sole means to drive the spool ring, the said driving means including a driving member running at constant rotary speed, a member to be driven thereby at varying rotary speed, means variably connecting the driving member to the driven member and having a cam follower; a cam, and resilient means to maintain the cam follower constantly in contact with the cam face.

5. A machine for winding toroidal coils, which machine comprises a spool ring to contain a supply of strand to be wound on a toroidal core, a guide ring to withdraw a continuously cyclically varying length of strand from the spool ring and to wind the same on the core, and means to drive the guide ring at a cyclically varying rate of rotation to withdraw strand from the spool ring at constant linear speed of the strand and thereby to drive the spool ring at constant speed of rotation, the withdrawal of the strand being the sole means to drive the spool ring, the said driving means including a driving member running at constant rotary speed, a member to be driven thereby at varying rotary speed, a toggle variably connecting the driving member to the driven member and having a cam roller on the central joint of the toggle, a cam, and resilient means to maintain the cam roller constantly in contact with the cam face.
6. A machine for winding toroidal coils, which machine comprises a spool ring to contain a supply of strand to be wound on a toroidal core, a guide ring to withdraw a continuously cyclically varying length of strand from the spool ring and to wind the same on the core, brake means to resist the rotation of the spool ring and thereby to impose a linear tension upon the strand being wound, and means to drive the guide ring at a cyclically varying rate of rotation to withdraw strand from the spool ring at constant linear speed of the strand and thereby to drive the spool ring at constant speed of rotation, the withdrawal of the strand being the sole means to drive the spool ring, the said brake means including a rotatable brake member driven by the spool ring, a helical friction member in frictional engagement with the brake member and so formed and wound that the normal drag of the brake member thereon tends to lessen the frictional engagement, and spring means to yieldingly maintain the frictional engagement and the said driving means including a driving member running at constant rotary speed, a member to be driven thereby at varying rotary speed, means variably connecting the driving member to the driven member and having a cam follower; a cam, and resilient means to maintain the cam follower constantly in contact with the cam face.

ROBERT PASH. 50
